UNITED STATES PATENT OFFICE.

THOMAS W. RYAN, OF CONCORD JUNCTION, MASSACHUSETTS.

BALL COCK FOR USE UPON HIGH AND LOW PRESSURE SYSTEMS.

Application filed February 14, 1924. Serial No. 692,722.

To all whom it may concern:

Be it known that I, THOMAS W. RYAN, a citizen of the United States, and a resident of Concord Junction, county of Middlesex,

5 State of Massachusetts, have invented an Improvement in Ball Cocks for Use upon High and Low Pressure Systems, of which the following description, in connection with the accompanying drawing, is a specification, 10 like characters on the drawing representing like parts.

This invention relates to improvements in ball-cocks and the general object thereof is to produce a ball-cock having a substantially 15 silent delivery for the liquid when used either upon high or low pressure systems and which will not unduly restrict the delivery of liquid when used upon low pressure systems.

20 A further object of the invention is to provide a ball-cock which is adapted for use without modification in all stories of high office and apartment buildings.

25 These and other objects and features of the invention will more fully appear from the following description and the accompanying drawing and will be particularly pointed out in the claims.

In the drawing:

30 Fig. 1 is a vertical longitudinal sectional view of an illustrative form of ball-cock construction embodying the invention, the piston and baffle plates being illustrated in elevation, and in which the piston is actuated by a single ball-controlled lever;

Fig. 2 is a sectional view on line 2—2, Fig. 1, looking downwardly;

Fig. 3 is a sectional view on line 3—3, Fig. 1, looking downwardly; and,

40 Fig. 4 is a view, partly in section, of a modified form of ball-cock showing also a compound leverage for actuating the piston.

The present invention embodies certain improvements on the construction disclosed 45 in my prior Patent No. 1,163,370 granted December 7, 1915.

The preferred form of the invention illustrated in Figs. 1, 2 and 3 comprises a casing having a cylindrical portion 1 provided 50 at its inlet end with external screw threads 2 by which it is adapted to be connected to the usual coupling 3 which is mounted upon the wall 4 of the tank and is adapted to be connected to an inlet pipe. The 55 casing also is provided with an en-

larged, preferably a spheroidal section 5, having a downwardly curved extension 6 to which is connected a delivery pipe 7 which extends nearly to the bottom of the tank. The casing thus constructed is provided with a cylindrical chamber 8 and an enlarged outlet chamber 9. Preferably a partition 10 extends transversely through the enlarged portion of the chamber 9 and its downward extension and together with an upwardly extending boss 11 provides bearings for an enlarged cylindrical portion 12 of the piston 13. The transverse partition 10 also serves to deflect the flow of liquid from the discharge opening and to cause 70 the eductive action of the stream to prevent leakage through the outer bearing.

The casing is also provided with upwardly and laterally extending arms 14 in which the pivots 15 of the ball lever 16 are mounted, the ball lever 16 being actuated by the usual ball (not shown) connected to the arm 17 which is adjustably secured to the ball lever 16 by a set screw 18. The ball lever desirably is bifurcated and the arms thereof connected by a shaft 19 preferably having thereupon an antifriction roller 20 which engages the walls of a horizontal slot 21 in the flattened upper end 22 of the piston. A valve seat 23 is located at the inlet end of the cylindrical portion of the casing and desirably is of the form shown comprising a cylindrical portion which fits tightly within the casing and has at its lower end an outwardly extending conoidal portion which abuts against complementary conoidal walls in the end of the casing. A washer 24 is interposed between the lower end of the valve seat 23 and the base of the enlarged portion of the coupling 3 so that 95 when the casing is screwed into the coupling the valve seat will force the washer tightly against its seat in the coupling and provide a tight joint. The end of the piston 13 is provided with a valve 25 having a washer 100 26 which co-operates with the valve seat 23.

The construction thus described may be and preferably is substantially identical with that disclosed in my prior patent aforesaid. In the construction disclosed in the prior 105 patent the piston is provided with a series of baffle plates alternately disposed on opposite sides of the piston with their adjacent edges overlapping these baffle plates acting to cause the liquid to flow through the cylin- 110

2
drical chamber of the casing in sinuous paths so that the interference and eddying of the respective currents impede the flow of water under high pressure, while by reason of the 5 lesser interference of the sinuous currents under low pressure the liquid is permitted to flow with such substantial freedom that the tank will be filled in the same time whether employed upon a high pressure or 10 low pressure system.

The object of the present invention is to provide a ball-cock which will be more nearly noiseless in its operation than valves heretofore constructed and also which will 15 be adapted to be employed upon more widely varying pressures than those for which previous ball-cocks have been designed.

The present invention broadly comprises the provision of a plurality of means for 20 producing currents of different characters within the cylindrical chamber of the ball-cock which will co-act to produce a substantially noiseless and uniform delivery of the liquid under widely different pressures.

25 In the preferred construction illustrated in Fig. 1 the lower portion of the piston 13 is provided with a spiral rib or flange 27 which desirably slidably fits within the casing and a plurality of baffle plates 28 which 30 extend from the piston in perpendicular relation to the axis thereof and slidably fit within the cylinder. These baffle plates 28 desirably are arranged at intervals with 35 their adjacent edges overlapping. It will, however, be understood that the baffle plates instead of being formed on the piston, which is more convenient in construction, may be formed in the casing itself and it will also be understood that these baffle plates 40 instead of being arranged in planes normal to the axis of the piston may be inclined relatively thereto within the spirit and scope of the invention.

By reason of this construction liquid entering through the inlet opening when the 45 valve is removed from its seat will follow a spiral course along a portion of the length of the piston and being obstructed by the baffles will be divided into a plurality of 50 sinuous streams the opposition and eddying of which will greatly reduce the flow under high pressures, while by reason of less interference and eddying under low pressure 55 will permit a relatively free flow of the liquid. Thus a substantially uniform discharge will be provided. The combined action of the spiral current and the divided current will cause the discharge of the liquid 60 from the outlet pipe into the tank to be substantially noiseless under all pressures.

The present construction illustrated in 65 Fig. 1 differs mainly from the prior construction disclosed in my patent aforesaid in that the spiral impetus of the current entering the chamber will increase the interfer-

ence and eddying of the liquid during its delivery through the portion of the casing in which it is impeded by the alternately arranged baffle plates, thus enabling the valve to be employed effectually upon higher pressure systems without materially affecting its efficiency upon low pressure systems. 70

The construction illustrated in Fig. 4 may be and preferably is similar to that illustrated and described with respect to Figs. 75 1, 2 and 3 except that additional means are provided for again modifying the flow of the liquid within the cylindrical casing and with the further exception that a compound leverage mechanism is illustrated for actuating the piston. 80

In the construction illustrated in Fig. 4 the piston is provided with the spiral 27 and with the oppositely disposed baffle plates 28 arranged at intervals, as illustrated and 85 described with respect to the construction shown in Figs. 1, 2 and 3. It is also provided with a pair of baffle plates 29 which are oppositely disposed and have their adjacent edges in alinement, but spaced apart 90 to provide passages for the liquid. It will be understood that any desirable number of pairs of baffle plates may be employed. The adjacent edges 30 of the baffle plates 29 desirably are arranged to present walls inclined to axial planes of the piston and preferably where a plurality of such passages are provided in each set of annularly disposed baffle plates the inclinations of the end 95 walls of the baffle plates are such as to cause 100 the liquid delivered through the passages to flow in spirals having the same direction of movement so that when the liquid is delivered into the enlarged outlet chamber 9 the streams will merge into a single stream 105 having a centrifugal movement.

By reason of this construction the flow of the liquid will be subjected to additional impedance particularly where very high pressures are employed. 110

It will be understood that the invention contemplates the use of any combination of two or more of the means for modifying the flow of liquid through the casing as may be best adapted for the varying conditions 115 under which the valves are to be installed.

Where the ball-cock is used upon exceedingly high pressures it is desirable that the compound leverage mechanism be employed for actuating the piston in order that the 120 valve may be closed with certainty against such high pressure.

In the construction shown in Fig. 4 a preferred type of compound leverage system is illustrated. In this construction the upper end of the casing is provided with upwardly extending arms 31 and 32. A lever 33 is fulcrumed upon trunnions 34 in the arm or arms 32 and preferably is provided with a cylindrical portion 35 which engages the 125 130

walls of the slot 21 in the flattened upper end of the piston. The lever 33 is pivotally connected at its other end to a link 36 the opposite end of which link is pivotally connected to the arm 37 of a lever 38 which is pivotally mounted on a shaft or trunnions 39 in the upper end of the arm 31, the lever 38 being secured to one end of the rod 17, the other end of which is provided with the 10 usual ball float (not shown).

In usual types of ball-cocks an aperture is provided in the spherical portion of the casing to receive a pipe leading to the delivery pipe of the tank for the purpose of supplying a sufficient amount of liquid during the filling of the tank after its discharge valve is closed to complete the water sealing of the trap from the ball after it has been emptied by siphonic action. In the present construction one side of the spherical portion of the casing is provided with a boss 40 having an aperture therethrough leading to the chamber 9, a portion of which aperture extends upwardly and receives the end of a pipe 41 leading to the delivery pipe of the tank. By reason of this construction the ball-cock is adapted to be placed more closely adjacent the wall of the tank and also presents a neater appearance.

30 In the construction disclosed in Fig. 4, as in that described in connection with Figs. 1, 2 and 3, the means for impeding the flow of liquid through the casing may be formed upon the casing instead of upon the piston within the spirit and scope of the invention.

It will be understood that the embodiments of the invention disclosed herein are of an illustrative character and are not restrictive, and that various changes in form, 40 construction and arrangement of parts may be made within the spirit and scope of the following claims.

Having thus described the invention, what is claimed as new, and desired to be secured 45 by Letters Patent, is:

1. A ball-cock comprising a relatively long casing having a cylindrical chamber with inlet and outlet openings, and a valve seat at the inlet end, a piston reciprocable in said 50 casing having a valve co-operating with said valve seat, means for actuating said piston and means within said chamber acting respectively to cause the stream of liquid to follow a spiral course around said piston in a portion of said chamber and to divide said 55 spiral stream into a plurality of streams in another portion of said chamber.

2. A ball-cock comprising a relatively long casing having a cylindrical chamber with 60 inlet and outlet openings, and a valve seat at the inlet end, a piston reciprocable in said casing having a valve co-operating with said valve seat, means for actuating said piston and means within said chamber acting respectively to cause the stream of liquid to

follow a spiral course around said piston in a portion of said chamber and to divide said stream into a plurality of streams and direct the same in sinuous courses in another portion of the chamber whereby the liquid by 70 interference and eddying causes greater retardation of the flow upon high pressure than upon low pressure.

3. A ball-cock comprising a relatively long casing having a cylindrical chamber with 75 inlet and outlet openings, and a valve seat at the inlet end, a piston reciprocable in said casing having a valve co-operating with said valve seat, means for actuating said piston and means within said chamber acting respectively to cause the stream of liquid to follow a spiral course around said piston in a portion of said chamber and in a plurality of sinuous streams in another portion of said chamber. 80

4. A ball-cock comprising a relatively long casing having a cylindrical chamber with inlet and outlet openings, and a valve seat at the inlet end, a piston reciprocable in said casing having a valve co-operating with said valve seat, means for actuating said piston and means within said chamber acting respectively to cause the stream of liquid to follow a spiral course around said piston in a portion of said chamber and to divide said 90 stream into a plurality of streams and direct the same in sinuous courses in another portion of the chamber whereby the liquid by interference and eddying causes greater retardation of the flow upon high pressure than upon low pressure and finally to discharge the liquid from said chamber in a plurality of streams flowing in the same general direction. 95

5. A ball-cock comprising a casing having 100 a relatively long cylindrical chamber with inlet and outlet openings, a valve seat at said inlet opening, a piston reciprocably mounted in said chamber having a valve co-operating with said valve seat, a spiral deflector on a portion of said piston, and baffles upon another portion of said piston arranged to change the path of the stream of liquid beyond said spiral deflector. 110

6. A ball-cock comprising a casing having 115 a relatively long cylindrical chamber with inlet and outlet openings, a valve seat at said inlet opening, a piston reciprocably mounted in said chamber having a valve co-operating with said valve seat, a spiral deflector on a portion of said piston and baffles upon another portion of said piston acting to divide the stream beyond said spiral deflector into a plurality of streams. 120

7. A ball-cock comprising a casing having 125 a relatively long cylindrical chamber with inlet and outlet openings, a valve seat at said inlet opening, a piston reciprocably mounted in said chamber having a valve co-operating with said valve seat, a spiral deflector on a 130

portion of said piston, and baffles acting to divide the stream beyond said spiral deflector into a plurality of sinuous streams.

8. A ball-cock comprising a casing having a relatively long cylindrical chamber with inlet and outlet openings, a valve seat at said inlet opening, a piston reciprocably mounted in said chamber having a valve co-operating with said valve seat, a spiral deflector on a portion of said piston and a series of baffle plates alternately arranged at intervals and overlapping at their adjacent ends and acting to divide the stream beyond said spiral deflector into a plurality of streams and to cause the same to flow in sinuous paths.

9. A ball-cock comprising a casing having a cylindrical chamber and an enlarged outlet chamber, a valve seat at the inlet end of said cylindrical chamber, a piston reciprocably mounted in said chambers having a valve to co-operate with said valve seat, a spiral deflector on said piston extending from said valve along a portion of the piston, a plurality of baffles alternately arranged at intervals and overlapping at their adjacent ends along another portion of the piston and other baffles beyond the first mentioned baffles having their adjacent ends in alinement, but spaced apart to provide passages for the liquid.

10. A ball-cock comprising a casing having a cylindrical chamber and an enlarged outlet chamber, a valve seat at the inlet end

of said cylindrical chamber, a piston reciprocably mounted in said chambers having a valve to co-operate with said valve seat, a spiral deflector on said piston extending from said valve along a portion of the piston, a plurality of baffles alternately arranged at intervals and overlapping at their adjacent ends along another portion of the piston and other baffles beyond the first mentioned baffles having their adjacent ends in alinement, but spaced apart presenting end walls inclined to the axial plane of said piston.

11. A ball-cock comprising a casing having a cylindrical chamber and an enlarged outlet chamber, a valve seat at the inlet end of said cylindrical chamber, a piston reciprocably mounted in said chambers having a valve to co-operate with said valve seat, a spiral deflector on said piston extending from said valve along a portion of the piston, a plurality of baffles alternately arranged at intervals and overlapping at their adjacent ends along another portion of the piston and a pair of baffles on said piston adjacent the outlet end of said cylindrical chamber having their ends in alinement and presenting parallel end walls inclined to axial planes of said piston.

In testimony whereof, I have signed my name to this specification.

THOMAS W. RYAN.
